Atty.

UNITED STATES PATENT OFFICE.

RICHARD LEUMANN, OF CHAILLY-SUR-LAUSANNE, SWITZERLAND.

DEVICE FOR REMOVING SHEETS SINGLY FROM A PILE OF SHEETS.

Application filed March 31, 1921. Serial No. 457,463.

(GRANTED UNDER THE PROVISIONS OF THE ACT OF MARCH 3, 1921, 41 STAT. L., 1313.)

To all whom it may concern:

Be it known that I, RICHARD LEUMANN, a citizen of the Republic of Switzerland, residing at Chailly-sur-Lausanne, Switzerland, have invented certain new and useful Improvements in a Device for Removing Sheets Singly from a Pile of Sheets (for which I have obtained a patent in Germany, dated August 29, 1914, No. 292,966); and I do hereby declare the following to be a clear, full, and exact description of the invention, such as will enable others skilled in the art to which it appertains to make and use the same, reference being had to the accompanying drawings, and to letters or figures of reference marked thereon, which form a part of this specification.

This invention relates to improvements in a device for removing sheets singly from a pile of sheets. Devices of this type are known in which the removal is effected by means of a pneumatic sucker device acting upon the lowermost of the sheets. The known devices present the disadvantage that the sheets resist to being bent during the removal and that a comparatively great suction action is needed.

The present invention has for its object to overcome this difficulty by positively causing the sheets to bend towards the sucker device in a downward direction. Thereby the resistance which occurs when sucking the single sheets at these points of curvature is decreased. In machines of this type it is seldom that the paper is absolutely flat, or if flat the sheet is buckled when initially seized by the sucker, and this buckling must be broken or overcome when the sheet is pulled down, by a transverse bend at the edge of the support for the stack of paper.

According to my invention the overhanging front portion of the stack is given a slight bend or curve downward, so that no buckling will occur, or if it does occur will be in front of the line of transverse bend and not increase the resistance to bending in the direction desired.

The force required to bend a sheet of

paper across a buckled portion is many times greater than that required to make a transverse bend in a flat sheet, or that required to continue the bending of an already bent sheet. The pneumatic sucker device therefore acts upon the ends of sheets with which this initial bending resistance has already been overcome, whereby a reliable working of the device results.

One mode of carrying the invention into effect is shown by way of example in the accompanying drawings, in which—

Fig. 1 is a vertical longitudinal section;

Fig. 2 a plan view and

Fig. 3 a cross-section of the device.

Figs. 4 and 5 show parts of the device in subsequent different working positions, and

Fig. 6 is an elevation showing in a diagrammatic manner the drive of the parts of the device.

1 denotes a receptacle containing the pile of sheets, the receptacle is supported by a stand 2. The bottom 3 of this receptacle is bent in a downward direction to a shape which is desirable for the sheets to be curved to. At the front end of the bottom of the receptacle a roller 4 turnably mounted on an axle 5 is provided serving to decrease the friction, when removing the lowermost sheet. A stirrup shaped member or sucker device 6 is rotatably mounted on set screws 80 6' acting as fulcrums, the member 6 is provided with projecting parts 8 and 9. The part 9 is arranged as a sucker and provided with bores 10 leading to a pipe 11 which is connected by a flexible hose 12 to an air-pump 44, 45 (Fig. 6). The parts 8 serve to support the sheets. Another stirrup-shaped organ 14 which may be hereinafter called the separator is turnably mounted in axles 13 and is provided with two tapered projections 15. The turning motion of the separator is derived from the driving shaft 29 by the interposition of a link 30 connected to one arm of a double-armed lever 31, adapted to swing about an axle 31' the other arm of which is provided with a roller

32 coacting with an eccentric 33 fixed to the shaft 29 (Fig. 6). A spring 20 causes the roller 32 to be pressed against said eccentric. The sucker device 6 is actuated in a similar manner by a roller 21 fitted to one arm of a bell crank lever 34 turnably mounted on the axle 31', the other arm of which carries a roller 35 cooperating with an eccentric 36 fixed to the driving shaft 10 29, a spring 22 causing the roller 35 to bear against the eccentric 36. Further a tong 23 is provided adapted to move up and down a vertical guide 37 and serving to grip the end of the sheet removed by the sucker 15 and to pull it out of the receptacle in a downward direction. The tong 23 is actuated by means of a link 38, connected to one arm of a bell crank lever 39 adapted to swing about a fixed fulcrum 40, the other 20 arm of the bell crank lever 39 being provided with a roller 41 engaging with a cam groove 42 of a cam disc 43 mounted on the driving shaft 29. The air pump 44, 45, which is shown in Fig. 6, is of the known 25 type comprising a piston 44 fixed to the stand 2, a movable cylinder 45 and a spring 46 arranged inside the pump and tending to force the cylinder in a downward direction for performing the suction stroke. A 30 bell crank lever 47 is adapted to lift the cylinder, which lever is turnably mounted on a fixed fulcrum 48, and provided at its one arm with a roller 49 coacting with an eccentric 50 fitted on the driving shaft 29. The 35 rear ends of the sheets are held by a sliding piece 24 adapted to be adjusted in the longitudinal direction of the sheets by means of a spindle 25 provided with a thumb nut 26 so that the piled up sheets are forced 40 to adapt the curved position at their front end. 27 denote supports fixed to the front plate of the receptacle 1 on which the sheets rest.

The operation of the above described device is as follows:

In the position shown in Figs. 1 and 6 the sucker 9 is in its forward position in touch with the lowermost sheet curved towards the sucker and which is held by 50 suction action. A rotation of the driving shaft 29 in the direction of the arrow permits of the bell-crank lever to turn in a clockwise direction, whereupon the spring 22 causes the sucker device to turn towards 55 the right into the position shown in Fig. 4, the sucked on sheet taking part in that movement. Immediately thereafter roller 32 rides off the nose of cam 33 and permits spring 20 to turn the stirrup-shaped element 60 14 and tapered projections thereon into the position shown in Fig. 4. Then the tong 23 is caused to move upward by the rotation of the driving shaft through the interposition of cam disc 43, cam groove 42, bell-crank lever 39 and link 38; the tong grips 65

the sheet and pulls it out of the container in its downward movement. The sheets remaining in the container are supported by the fixed supports 27 and the parts 15 of the separator as shown in Fig. 4. The separator 70 14 is in its lowest position when the sucker 9 acts upon the lowermost sheet (Figs. 1 and 6). As soon as the sucker 9 has moved past the parts 15 of the separator the latter is moved into its highest position. Thereby 75 if the sucker has from any reason partly removed also the next but lowermost sheet (Fig. 5) the latter is moved back towards the other sheets before it can be gripped by the tong. The relative arrangement of the eccentric 33 actuating the separator and of the cam groove 42 actuating the tong is such that the separator will first be moved into its highest position and then the tong performs its upward movement. 80 85

I claim:

1. In a sheet feeding device means to support a stack of sheets slightly inclined with their forward ends overhanging said means and downwardly flexed, means to force and hold the sheets in such position, a sucker device co-operating with the overhanging end of the lowermost downwardly bent sheet, and means to move said device to flex the lowermost sheet to a greater degree in the direction of initial flexure to thereby separate the front end of the lowermost sheet from the sheets above it, and means to seize and withdraw the lowermost sheet from the stack. 100

2. In a sheet feeding device, a receptacle having a bottom supporting a stack of sheets slightly inclined with their forward ends overhanging said bottom and downwardly flexed, the forward edges of the downwardly flexed sheets maintained in contact with the front wall of said receptacle, a sucker device, means to move said device to and from the lowermost sheet of the stack to flex said sheet to a greater degree in the direction of its initial flexure and thereby flex the forward end of the sheet from the stack, and means to seize and withdraw said sheet from the stack. 110

3. A sheet feeding mechanism, having a receptacle adapted to hold a pile of sheets in a slightly inclined direction, a sucker device co-acting with the front ends of said sheets, and means to cause a pressure to the back of the pile of sheets held in said receptacle to urge them against the front wall of said receptacle and to effect thereby a flexing in the downward direction toward said sucker of the front ends of the sheets, whereby the resistance offered by said sheets to the action of said sucker device that causes a further flexing of said sheets in the same direction is reduced. 120 125

4. In a sheet feeding device, a receptacle having a downwardly curved bottom sup- 130

porting a stack of sheets slightly inclined with their forward ends overhanging the front edge of said bottom and against the front wall of said receptacle, means in said receptacle to maintain the sheet stack inclined to the rear, a sucker device to engage and separate the front end of the lowermost sheet from the stack by flexing it in the direction of initial flexure, and means to seize and remove the so separated sheet. ¹⁰
In testimony that I claim the foregoing as my invention, I have signed my name.

RICHARD LEUMANN.
